TOASTER CASE

Henry L. Olson and Robert A. Miller, Grand Haven, Mich., assignors to Camfield Manufacturing Company, Grand Haven, Mich., a corporation of Michigan

Application June 9, 1950, Serial No. 167,000

5 Claims. (Cl. 220—4)

1

The herein disclosed invention relates to cases for toasters and particularly electric toasters and resides in providing a case which may be quickly and easily assembled.

Another object of the invention resides in providing a case in which the parts can be fabricated at a minimum expense.

A still further object of the invention resides in providing a case which will be attractive in appearance and which will utilize parts having joints generally horizontally arranged with respect to the case.

Another object of the invention resides in constructing the case with a lower case section open at the top and with an upper case section open at the bottom, said case sections having marginal portions adapted to register with one another.

An object of the invention resides in constructing the case with catch means acting between the marginal portion of the upper and lower case sections for holding the same in assembled relation.

A feature of the invention resides in constructing one case section with a perimetrically extending rabbet at the marginal portion thereof and in which the marginal portion of the other case section is adapted to be received.

An object of the invention resides in constructing the lower case section in two parts, one part forming a side wall and fragments of the end walls of the case and the other part forming the other side wall and other fragments of the end walls of the case.

Another object of the invention resides in connecting said fragments of the end walls together by means of a bar secured thereto at the marginal portions thereof and holding the parts in proper spaced relation.

An object of the invention resides in constructing the upper case section with an inwardly turned lip forming a catch and being part of said catch means, said lip being adapted to engage beneath the bar and hold the sections in assembled relation.

Another object of the invention resides in arranging the bars in inclined relation so that said lips are forced apart as the case sections are brought together and whereby the lips will spring back in place beneath the bars when the sections are in proper position.

Another object of the invention resides in providing end pieces for the lower case section and in attaching the same to the upper portion of the lower case section through the bars.

Other objects of the invention reside in the

2

novel combination and arrangement of parts and in the details of construction hereinafter illustrated and/or described.

The case illustrated consists of a lower case section constructed of two spaced parts. These parts are formed to provide side walls for the case and fragments of the end walls of the same. The lower case section is open at the top and is formed with a marginal portion having a perimetrically extending rabbet therein. The marginal portions of the two fragments of the lower case section are connected together by means of bars which extend across the same and are secured thereto. Attached to the ends of the lower case section are end pieces which are secured at their upper ends to the said bars and which are further secured to the lowermost portion of the fragments of the lower case section. Overlying the lower case section is an upper case section which is open at the bottom and which is formed with a marginal portion adapted to be received within the rabbet in the lower case section. The upper case section has inwardly turned lips forming catches adapted to be forced into position beneath the connecting bars and serving to hold the case sections attached. These bars are arranged in inclined relation to force the lips apart when the two case sections are brought together, stressing the upper case section to cause the lips to spring back into position beneath said bars.

In the drawings:

Fig. 1 is an elevational sectional view of a case illustrating an embodiment of the invention and taken on line 1—1 of Fig. 2.

Fig. 2 is a cross sectional view of the case taken on line 2—2 of Fig. 1.

Fig. 3 is a plan view of the end portion of the lower case section of the invention.

Fig. 4 is a fragmentary elevational longitudinal sectional view of a part of the case structure shown in Fig. 1 and illustrating the position of the parts before assembly.

The instant invention consists of a lower case section 10 open at the top and an upper case section 11 open at the bottom and adapted to be applied to the case section 10. Both of these case sections are principally constructed of sheet metal which is stamped in suitable dies in the desired form and which are assembled as will be subsequently described.

The lower case section 10 consists of two parts 12 and 13 which are spaced from one another. The part 12 forms a side wall 14 of the case and has two fragments 15 extending inwardly there-

from and which form parts of the end walls of the case. The part 13 is similarly constructed to form a side wall 21 and has fragments 15 forming portions of the end walls of the lower section 10 of the case. Both of the parts 12 and 13 have flanges 45 projecting inwardly from the walls 14 and 21 and from the fragments 15 and 22. The upper marginal portions 16 of the parts 12 and 13 are offset from the side and end walls to form rabbets 17 in said lower case section 10 providing upwardly facing shoulders 18. These rabbets are relieved at the lower parts of the same as indicated at 19 to form projections 20 which extend outwardly beyond the innermost portions of the shoulders 18. The marginal portions 16 are arranged in inclined relation with respect to the side walls 14 and 21, projecting inwardly therefrom.

For securing the parts 12 and 13 together two bars 23 are employed. These bars extend across the marginal portions 16 of the fragments 15 of the parts 12 and 13 and are offset as designated at 24 to bring the major portion of said bars in substantial alignment with the portions 16. The said bars may be secured to the portions 16 by means of spot welds 25, or the same may be riveted thereto. The bars 23 hold the parts 12 and 13 in proper spaced relation.

The upper case section 11 is dome-shaped in form having sides 26, ends 27 and a top 28. This section is preferably constructed from a single piece of sheet metal drawn to the desired shape. The case section 11 is open at the bottom and is formed with a marginal portion 29 which is adapted to be received in the rabbet 17 formed by the offset marginal portion 16 of the case section 10. The marginal portion 16 serves to guide the two case sections into register. When the parts are in proper position the lower edge 30 of the marginal portion 29 rests upon the shoulder 18 and the marginal portion 29 engages the projections 20. The top 28 is formed with openings 31 through which the bread to be toasted may be inserted into the toaster proper contained within the case.

For holding the case sections attached to one another catch means is employed which utilizes the two bars 23. In addition lips 32 are formed on the lower marginal portions 29 at the end walls 27 of the upper case section 11 as best shown in Fig. 4 and which are adapted to engage the bars 23. The bars 23 are arranged in inclined relation, the same as the marginal portions 16 of the lower case section 10. When the upper case section 11 is forced downwardly over the marginal portions 16 and the bars 23 of the lower case section the lips 32 are sprung apart and when the same pass the lower edges 33 of the bars 23, the said lips spring back into position beneath said bars and hold the sections in assembled relation. It will thus be seen that the lips 32 form catches constituting a part of the catch means and which have upwardly facing shoulders engaging the shoulders on the bars 23 formed by the lower edges 33 thereof.

For closing the space between the parts 12 and 13 of the lower case section 10 two end pieces 34 and 35 are employed. These end pieces being identical in construction only the end piece 34 will be described in detail. This end piece is constructed from a plastic material and has a wall 36 overlying the vertical marginal portions 37 of the fragments 15 and 21 of the parts 12 and 13. This wall is curved to conform to the curvature of the parts 12 and 13 and fits snugly against the frag-

ments 15. The wall 36 has lugs 56 on the same which engage the edges 57 of the marginal portions 37 to hold the parts in proper position. At the upper ends of the end pieces 34 and 35 are formed projections 38 which serve as handles by means of which the toaster may be readily carried about. The end pieces 34 and 35 are formed ornamental to enhance the appearance of the case. The upper end of the end piece 34 is secured to the toaster by means of a clip 39. Clip 39 has a base 40 which overlies two bosses 41 formed on the end piece 34. Screws 42 pass through the base 40 and are screwed into these bosses. The clip 39 has a wide finger 43 which is adapted to engage in back of the bar 23 to hold the upper end of the end piece 34 in position. The clip 39 is constructed of resilient material so that the upper end of the end piece is urged to fit snugly against the toaster case proper. The lower end of the end piece 34 has an inturned portion 44 which is disposed beneath the flanges 45. Feet 46 are formed on these portions and which support the case proper above the surface on which the feet rest to provide ventilation. The end piece 34 is attached to the flanges 45 by means of screws 47 which extend through the feet 46 and are screwed into the flanges 45.

The bottom of the case is closed by means of a bottom 48. This bottom consists of two end members 49 and 50 and a closure 51 disposed intermediate said end members. The closure 51 is hinged connected to the member 49 by means of hinges 52 and is detachably secured to the end member 50 by means of a spring clip 53. The end members 49 and 50 are held attached to the case by being disposed between the flanges 45 of the parts 12 and 13 and the portions 44 of the end pieces 34 and 35. Screws 49 also pass through these said end members.

For the purpose of attaching the mechanism of the toaster to the case the flanges 45 are constructed with ears 54 and through which suitable screws extend and which are screwed into parts of the mechanism.

The use of the invention is obvious. The mechanism is first attached to the ears 54 on flanges 45 and the various operating levers projected through slots 55 in the end pieces 34 and 35. When the case is to be closed the upper case section 11 is merely placed upon the lower case section 12 with the marginal portion 29 of said upper case section extending about the marginal portion 16 of the lower case section. The upper case section is then forced downwardly which causes the lips 32 to engage the bars 23 and to be forced apart as the top section descends. When the said lips pass below the edges 33 of the said bars, the lips snap in position and the upper section is rigidly secured to the lower section.

The advantages of the invention are manifest. The device is extremely simple in construction and can be readily fabricated by methods and equipment now available for the purpose. With the invention, no screws or other fastening members are exposed, and the appearance of the case is greatly enhanced. The joint between the upper and lower case section extends in a horizontal direction so that the case is extremely attractive in appearance. The end pieces used with the case serve to close the spaces between the two parts of the lower section of the case thereby simplifying the construction of the case. The assembly of the upper and lower case section is extremely simple and is accomplished by merely placing the

upper section over the lower and pressing the two together.

Changes in the specific form of the invention, as herein described, may be made within the scope of what is claimed without departing from the spirit of the invention.

Having described the invention, what is claimed as new and desired to be protected by Letters Patent is:

1. In a case for toasters, a lower case section consisting of two oppositely disposed parts forming the lower portions of the side walls of the case and fragments of the lower portions of the end walls of the case, the ends of said fragments being spaced from one another, end pieces closing the spaces between said fragments and secured to said case, the upper marginal portions of the two parts of the lower case section having inwardly disposed offsets forming outwardly facing open rabbets terminating at the facing ends of said fragments, bars extending across and secured to the ends of said offsets and holding the parts of the lower case section in position, said bars lying substantially in continuation of said offsets and being spaced from said end pieces to leave the outer and under surfaces of said bars free, an upper case section open at the bottom and having a lower marginal portion received in the rabbets of the lower case section and overlying the outer surfaces of said bars, and inwardly turned lips at the ends of the upper case section and disposed at the lower edges of the marginal portions thereof, said lips having upwardly facing surfaces engaging the under surfaces of the bars to hold the section in assembled relation.

2. In a case for toasters, a lower case section consisting of two oppositely disposed parts forming the lower portions of the side walls of the case and fragments of the lower portions of the end walls of the case, the ends of said fragments being spaced from one another, end pieces closing the spaces between said fragments and secured to said case, the upper marginal portions of the two parts of the lower case section having inwardly disposed offsets forming outwardly facing open rabbets terminating at the facing ends of said fragments, bars extending across and secured to the ends of said offsets and holding the parts of the lower case section in position, said bars being disposed in inclined relation and lying substantially in continuation of said offsets and being spaced from said end pieces to leave the outer and under surfaces of said bars free, an upper partly resilient case section open at the bottom and having a lower marginal portion received in the rabbets of the lower case section and overlying the outer surfaces of said bars, and inwardly turned lips at the ends of the upper case section and disposed at the lower edges of the marginal portions thereof, said lips having inwardly disposed edges adapted to engage the outer surfaces of said bars and to spring the upper case section upon downward pressure thereon and to force said lips below said bars, said lips having upwardly facing surfaces engaging the under surfaces of the bars to hold the section in assembled relation, said lips through the resiliency of said upper case section springing in place beneath said under surfaces of said bars when the lips pass below the same.

3. In a case for toasters, a lower case section consisting of two oppositely disposed parts form-

ing the lower portions of the side walls of the case and fragments of the lower portions of the end walls of the case, the ends of said fragments being spaced from one another, end pieces closing the spaces between said fragments and secured to said case, the upper marginal portions of the two parts of the lower case section having inwardly disposed offsets forming outwardly facing open rabbets terminating at the facing ends of said fragments, bars extending across and secured to the ends of said offsets and holding the parts of the lower case section in position, an upper case section open at the bottom and having a lower marginal portion received in the rabbets of the lower case section and overlying the outer surfaces of said bars, and inwardly turned lips at the ends of the upper case section and disposed at the lower edges of the marginal portions thereof, said lips having upwardly facing surfaces engaging the under surfaces of the bars to hold the section in assembled relation.

4. In a case for toasters, a lower case section consisting of two oppositely disposed parts forming the lower portions of the side walls of the case and fragments of the lower portions of the end walls of the case, the ends of said fragments being spaced from one another, end pieces closing the spaces between said fragments and secured to said case, the upper marginal portions of the two parts of the lower case section having inwardly disposed offsets forming outwardly facing open rabbets terminating at the facing ends of said fragments, bars extending across and secured to said end fragments, an upper case section open at the bottom and having a lower marginal portion received in the rabbets of the lower case section and overlying the outer surfaces of said bars, and inwardly turned lips at the ends of the upper case section and disposed at the lower edges of the marginal portions thereof, said lips having upwardly facing surfaces engaging the under surfaces of the bars to hold the section in assembled relation.

5. In a case for toasters, a first case section having perimetrically extending marginal portions formed with inwardly disposed offsets providing outwardly facing open rabbets, said offsets having spaced facing ends providing a space therebetween, a bar extending across and secured to the ends of said offsets, said bar having an outer side surface extending substantially in continuation of the outer surfaces of said offsets and innermost and outermost edge surfaces angularly disposed with reference to the side surface thereof, a second case section having a marginal portion received in said rabbets and overlying the outer side surface of said bar, and an inwardly turned lip at the marginal portion of said second case section entering said space and having a surface facing the inner edge surface of the bar and engageable therewith to restrain separation of the case section.
